LINING FOR VESSELS

John Carlstrom, Port Arthur, Tex., assignor to
The Texas Company, New York, N. Y., a corporation of Delaware

Application June 17, 1932, Serial No. 617,832

3 Claims. (Cl. 196—133)

This invention relates to interior linings for the protection of vessels in which the treatment of materials corrosive to the walls thereof may be carried on, and refers particularly to the lining of ordinary steel vessels used in the pressure cracking of hydrocarbon oil.

In the pressure cracking of petroleum fractions corrosive compounds are encountered or are developed in the decomposition process which attack the steel walls of the vessels in which the treatment is being carried on, which has the effect of deteriorating or corroding away the metal very rapidly.

In practice the shells of vessels of this class are fabricated of much heavier material than is necessary merely to withstand the temperatures and pressures ordinarily employed, for the reason that in the course of operation the interior surfaces of the walls are deteriorated to such an extent that their strength is materially impaired. Accordingly it has been necessary to allow for a certain amount of deterioration by making the walls of extra thickness. It will be seen that the expense of constructing large vessels is multiplied rapidly as the thickness of the shells is increased. It is therefore of advantage to provide an effective lining which is adapted to protect the interior surface of a vessel and which may be readily repaired or removed from and replaced in the vessel.

According to the usual practice, metallic or alloy metal linings have been provided which are bonded to the vessel proper and are designed to present an impervious shield against contact of the material being treated with the walls of the vessel. Among the chief difficulties encountered in linings of this type is the difference in the coefficient of expansion of the material of which the vessel itself is made and that of which the lining may be made, and that many substances cannot be bonded effectively to the steel of which the vessel is made.

In instances where linings are bonded to the vessel and where the coefficient of expansion of the lining material is less than that of the vessel, the vessel has a tendency to expand away from it in which event the lining, not being strong enough to withstand the pressure usually employed, may rupture or may be expanded by the force of the pressure to the larger size and buckle when the temperature is next lowered to atmospheric. On the other hand where the coefficient of expansion of the lining is greater than that of the vessel it will have a tendency to bulge and buckle when the temperature is raised, in which

event the lining may eventually rupture at the point of buckling.

I have discovered that in the pressure cracking of hydrocarbon oil it is not necessary to completely isolate the walls of the vessel from the inclosed oil or vapor and that moreover if certain of the products of reaction such as carbon or coke particles are permitted to deposit on the surface thereof they may form a protective coating which is itself resistant to corrosion. I have further discovered that corrosion often proceeds most rapidly from the clean surface of a metal and that certain of the forming sulfides and other corrosion products may themselves, as a coating, be a protection against more advanced or continued corrosion of the steel walls. It is noted, however, that in the vapor space of cracking vessels, where corrosion is more pronounced, the walls of the vessel are normally swept relatively clean of any protecting film such as coke and that any protection against corrosion which would otherwise be afforded by deposits of coke or of corrosion products, such as sulfides, is thereby continuously destroyed.

The invention contemplates a relatively cheap lining formed of a plurality of sections of sheet metal which is adapted to fully cover and protect the surface or portions thereof of the vessel to which it may be applied. The sections comprising the lining overlap thereby forming a continuous lining surrounding the interior wall of the vessel.

It is an object of the invention to provide a lining of light simple construction which may be securely fastened or anchored to the walls of the vessel and which may be readily repaired or removed from and replaced in the vessel.

Another object of this invention is to provide a lining of light simple construction having the same coefficient of expansion as the vessel.

The invention will be more fully understood by referring to the following description and the accompanying drawing in which:

Fig. 1 is a view in sectional elevation of an interiorly lined vessel showing a preferred embodiment of my invention.

Fig. 2 is a view taken on the line 2—2 of Fig. 1.

Fig. 3 is an enlarged view in sectional elevation of the lining joints shown on the right hand side of Fig. 1.

Fig. 4 is an enlarged view of the pipe connection and its lining shown on the left hand side of Fig. 1.

Referring now to Fig. 1, an upper section of a vertical cylindrical vessel having a convex end

or dome is illustrated which may be used in the pressure cracking of hydrocarbon oil. The apparatus shown is intended to be that portion of a vertical expansion chamber which is situated 5 above a level of liquid carried in the vessel, which is usually referred to as the vapor space and in which the corrosive action of the existing vapors is especially pronounced. That portion of the vessel shown comprises a shell portion 1, a man- 10 way 2, a pipe connection 3, a vapor outlet pipe 4 and the lining.

While I have shown a vertical cylindrical vessel having a convex end, it is to be clearly understood that my invention is not limited to a vessel shaped in this manner. The vessel may be 15 of any shape and may be positioned in a horizontal or slanting position without departing from the scope of the invention.

According to the invention, the lining may 20 include one or more circumferential rows of rectangular plate sections 10, depending upon the vertical dimension of the shell portion to be lined, and a row of rectangular plate sections 11. These plate sections are individually rolled to fit the 25 interior curvature of the shell and the adjacent vertical edges of the plates may overlap, as at 12, and the overlapping plates may be bonded together at any desired intervals by tack welding, as at 13. The plates 10 may be supported by 30 welding the entire top edges thereof to the shell 1, as at 14, or by tack welding the top edges in several places to the shell. The plates 11 may likewise be supported at the top edges thereof, either by welding directly to the shell or by welding, as at 15, to a circular flat bar 16 which may 35 be divided into arcuate sections whose ends abut and is preferably welded to the shell 1 as at 17. A flat bar 18 which may also be divided into arcuate sections may be fastened to the plates 10 at 40 their lower rim by tack welding at appropriate intervals for retaining the plates in proper circular alignment with the shell. A flat bar 19 of similar construction to the bar 18 may be secured at 45 the lower edge of the plates 11 which is preferably appropriately situated and of sufficient width to bridge any gap existing between the plates 11 and the plates 10.

Segmental dome plates 20 are provided for 50 lining the convex end, the adjacent edges of which form abutting joints. The dome plates are preferably supported at their lower or flaring ends by welding them to the shell, as at 25, and along their abutting joints by supporting bars 26. The bars 26 are preferably supported at their 55 lower ends by welding, as at 28, to a sectional flat bar 27 which is preferably secured to the upper ends of the plates 11 or to the flat bar 16 by welding, as at 29. At the top of the dome, a disc-like plate 30 is preferably attached to the inwardly protruding vapor outlet pipe by welding as at 60 31. The plate 30 is adapted to overlap and support the upper or tapering ends of the dome plates 20 and also the bars 26, the upper ends of which 65 abut and are welded to the peripheral edge of the disc 30.

A lining is provided for the manway 2 comprising 70 a thimble or sleeve 33 which may be secured therein by welding the outer end to the neck of the manway, as at 34, and by flaring the inner end against the wall lining and welding it to the lining, as at 35.

The pipe connection 3, which in most cases is 75 provided for communication to an adjoining vessel, may preferably be lined from one vessel through to the other. The connection to the lining

is shown clearly in Fig. 4. The lining consists of a sleeve 41 of such length as to project slightly past the inwardly protruding end of the connection 3. A disc-like member 42, whose surface is compressed to form a circular concavity between the end of the pipe lining 41 and the vessel lining, is welded at its inner edge to the end of the pipe lining, as at 43, and at its outer or peripheral edge to the vessel lining, as at 44, and serves to protect the end of the pipe connection where it is welded to the wall of the vessel.

My invention is not limited to any particular method of welding as any of the known methods may be employed.

It will be seen that an effective lining has thus 15 been provided which is inexpensive to install and which may be repaired or removed from and replaced in the vessel with a minimum amount of effort. In the novel form of construction 20 shown, the adjacent plates overlap and this feature is of value especially in lining partly worn or even new vessels in which variations in diameter exist as between different vertical locations. The form of lining shown is intended particularly for use in conjunction with ordinary 25 mild steel having approximately the same coefficient of expansion as the material of which the vessel itself is constructed. By using a metal for lining having the same coefficient of expansion as the vessel itself, it will be readily seen 30 that the tendency of the lining to buckle or bulge with respect to the vessel when subjected to temperature variations is obviated. Moreover the lining may be extended throughout the vessel the lower end being arranged substantially the 35 same as the upper.

While I have shown and described an interior lining for a vessel used in the cracking of hydrocarbon oils, it is to be understood that my invention is not limited to this type of vessel. 40 Obviously the invention is applicable to any type of vessel in which a protective lining is desirable. Moreover, the invention is not limited to a vessel of ordinary steel as any metal or metal alloy may 45 be used to construct the vessel. In carrying out the invention, it is contemplated that the lining for the vessel should be made from the same metal or metal alloy as that used in the vessel itself, or from a metal or metal alloy having approximately the same coefficient of expansion as 50 the metal or metal alloy used in the vessel. As an example of the latter, the vessel may be made from ordinary steel whose coefficient of expansion is .0000061 per degree F. and the liner from a low chrome alloy, e. g. 4-6% chromium, whose 55 coefficient of expansion is .0000062 per degree F.

Obviously many modifications and variations of the invention, as hereinbefore set forth, may be made without departing from the spirit and scope thereof, and therefore, only such limitations 60 should be imposed as are indicated in the appended claims.

I claim:

1. In a vertical cylindrical vessel having a convex end, an interior lining comprising a plurality of rectangular plate sections adapted to form a plurality of continuous rings around the interior of the vessel, each of said sections having vertical and horizontal edges with the vertical edges overlapping and the horizontal edges welded to the vessel at their upper ends and braced at their lower ends, segmental plate sections adapted to form a lining for the convex end, each of said plate sections having a flaring end and a tapering end, the flaring end being welded to the side 75

5 of the convex end and the tapering end being secured near the center thereof, a circular flat bar overlapping and attached to the flaring ends of the segmental plate sections and overlapping the upper ends of the top ring of rectangular plate section, a circular flat bar attached to the lower ends of the plate sections of each ring adapted to brace the attached plate sections against the vessel and overlapping the upper 10 ends of the next lower ring of plate sections, and a circular plate attached to the center of the convex end adapted to overlap and secure the tapering ends of the segmental plate section.

10 2. In a vertical cylindrical vessel having a convex end, an interior partial lining comprising a circular flat bar welded to the upper portion of the vertical vessel, a plurality of rectangular plate sections adapted to form a plurality of continuous rings around the interior of the vessel, each of said sections having vertical and horizontal edges with the vertical edges tack welded together at a plurality of points and the upper horizontal edges welded to said circular flat bar, a circular flat bar welded to the lower ends of 20 the plate sections of each ring adapted to brace the attached plate sections against the vessel, and overlapping the upper ends of the next lower ring of plate sections, segmental plate sections adapted to form a lining for the convex end,

each of said plate sections having a flaring end and a tapering end, the flaring end being welded to the convex end near the upper edge of the first mentioned flat bar, a circular flat bar overlapping and welded to the first mentioned flat bar and the flaring ends of the segmental plate sections, a circular plate attached to the center of the convex end overlapping and supporting the tapering ends of the segmental plate sections, and supporting bars for the segmental plate sections, having one end welded to the third mentioned flat bar and the other end welded to the peripheral edge of the circular plate.

15 3. A vessel adapted for refining hydrocarbons comprising a hollow cylindrical metal body member, a plurality of metal rings forming liner sections arranged end to end longitudinally of said cylindrical body adjacent the wall of said body, each of said rings comprising a plurality of metal sheets, means uniting the adjacent longitudinal edges of said sheets, means securing one edge of each of said sheets forming the peripheral edge of each ring to the wall of said cylindrical body and means for holding the opposite edges of said sheets to maintain them in position against the 20 wall of the cylindrical body, said last mentioned means being affixed to said sheets only.

25 JOHN CARLSTROM.
